UNITED STATES PATENT OFFICE.

LUIGI GHINELLI, OF ROME, ITALY.

MARINE OR THE LIKE VESSEL.

Application filed July 17, 1919. Serial No. 311,678.

(GRANTED UNDER THE PROVISIONS OF THE ACT OF MARCH 3, 1921, 41 STAT. L., 1313.)

To all whom it may concern:

Be it known that I, LUIGI GHINELLI, residing at Via Gaetano Donizzetti 22, Rome, in the Kingdom of Italy, have invented certain new and useful Improvements to Marine or the like Vessels, of which the following is a specification.

The present invention relates to non-sinkable vessels; and it proposes a construction embodying certain improved features, hereinafter fully described, according to which the sides and bottom of the hull, as well as the plating of the decks, are lined with water-tight cells, all independent of one another and extending from end to end of the vessel and from the keel to a point above the water line, so that a large watertight zone is thus produced which encloses the vessel and affords a high coefficient of buoyancy.

In consequence of the formation of this water-tight zone, any injury to the hull of the vessel will affect only the cells at the particular point damaged, or in the immediate vicinity of such point, leaving in any case a sufficient number of cells intact to balance and counteract the weight of the incoming water.

In the accompanying drawing, Figures 1 and 2 are sectional views of two slightly different forms of vessels embodying the invention, and Fig. 3 is a diagrammatic plan view of Fig. 2.

As shown in the drawing, the space between the outer and inner plating or walls at the sides and bottom of the hull of the vessel is filled or lined with cube-shaped cells 1 arranged tier on tier in parallel contacting rows which extend from stem to stern of the vessel and which occupy the entire bottom of the hull, the rows at the sides of the vessel extending upwardly to a point above the water line, as has already been stated. The hull represented in Fig. 2, although double-walled, is single-bottomed, whereas in the construction illustrated in Fig. 1, the hull comprises an additional inner or false bottom; and in the latter instance, this auxiliary bottom is likewise constructed with cells, as indicated at 3. A similar arrangement of cells 2 is also applied to the several decks.

The cells are preferably constructed of aluminum or other suitable light and thin

sheet metal reinforced with a strong, light framework of wood, the metal serving to render the cells water-tight, while the wooden framework acts to hold them in place, and to prevent them from being crushed by the pressure of the water in case the vessel is struck and flooded, in which instance the buoyancy of the wood will also serve to compensate for the higher specific gravity of the metal. The size of the cells depends, of course, upon the tonnage of the vessel and upon the size of the compartments or chambers between the outer and inner plating as well as upon the particular portions of the chambers in which they are located; but they must entirely fill such chambers so as to leave no spaces between them.

The vessel may also be constructed in such a way as to provide in close contact with the side walls of the hull and between the decks two opposite passages 5 (Figs. 2 and 3), which extend the entire length of the vessel and open into each other at their ends. These passages or galleries may be utilized for storing small goods; but they should not be made too wide because in the event that the hull is penetrated from the outside from any cause, they will be flooded, and the water entering and filling them will assist in keeping the vessel on an even keel. The several compartments 6 for the machinery, coal, stores, etc., and for the housing of the passengers and crew are built in the space enclosed by the two passages 5, and are arranged symmetrically with longitudinal and vertical or transverse bulkheads provided with water-tight doors 4 (Fig. 2), ventilation being obtained by means of air-tubes (not shown) projecting a suitable distance above the top deck. As the compartments 6 are water-tight, the passengers and crew will be in safety, even if the vessel should be flooded, the presence of the compartments tending to increase the difficulty of sinking the vessel.

I claim as my invention:

A vessel constructed with a double-walled hull, the inner and outer sections of which are spaced apart; a filling of separate, relatively small, cubical, air-tight boxes disposed in contacting, parallel rows in the space between said wall sections and extending from end to end of the vessel and

on opposite sides from the keel to a point above the water line and entirely filling said space between said inner and outer wall sections; a pair of opposite passages located between the decks of the vessel in close contact with the side walls of the hulls and extending the entire length of the vessel, said passages opening into each other at their ends; and symmetrically-arranged, water-tight compartments built in the space

enclosed by said passages and having water-tight doors.

In testimony whereof I have hereunto signed my name in the presence of two witnesses.

LUIGI GHINELLI.
